UNITED STATES PATENT OFFICE.

WESTON M. FULTON, OF KNOXVILLE, TENNESSEE, ASSIGNOR TO THE FULTON COMPANY,
OF KNOXVILLE, TENNESSEE, A CORPORATION OF MAINE.

HEAT-CONTROLLING DEVICE.

No. 894,947.

Specification of Letters Patent.

Patented Aug. 4, 1908.

Application filed March 24, 1905. Serial No. 251,912.

To all whom it may concern:

Be it known that I, WESTON M. FULTON, of Knoxville, Tennessee, have invented a new and useful Improvement in Heat-Controlling Devices, which invention is fully set forth in the following specification.

This invention relates to heat controlling devices, and particularly to those in which the thermo-sensitive properties of a gaseous body are utilized to impart motion to a collapsible and expandable vessel to automatically actuate a damper or valve mechanism for controlling the generation of heat.

The object of this invention is to provide a heat controlling device which may be applied to stoves, furnaces, and the like, which will quickly respond to slight variations in temperature and may be set to operate between any predetermined maximum and minimum temperature limits and remain inoperative at temperatures outside of these limits.

A further object is to provide a device which will be simple in construction, durable, and can be readily adapted to existing stoves and furnaces with a minimum expenditure of time and labor, and which will maintain the temperature of the space to be heated uniform, and effect a marked saving in the quantity of fuel burned by preventing extremes of heat.

In order that the invention may be more readily understood, certain mechanical expressions of the inventive idea involved are shown in the accompanying drawings, which are designed merely as illustrations to assist in the description of the invention, and not as defining the limits thereof.

In the accompanying drawings—Figure 1 shows in elevation and part vertical section one form of the invention as applied to a heating stove. Fig. 2 is a rear elevation of the apparatus shown by Fig. 1. Fig. 3 shows an enlarged vertical section of a modification of the thermo-sensitive device and the manner of supporting the same. Fig. 4 is a further modification; and Fig. 5 shows the application of the invention to an oven.

Referring to Fig. 1, 1 is a collapsible and expandable vessel of corrugated sheet-metal having rigid end walls 2 and 3, one of which is fast and the other free to move, the latter being preferably made re-entering and extending nearly to the end wall 2. Both end walls are securely attached to the ends of the corrugated portion by welding or brazing,

thereby forming a hermetically closed vessel. Surrounding vessel 1, is an outer casing 4, which may assume various forms, and, as shown in Fig. 1, completely incloses the inner collapsible vessel 1. To the top wall of casing 4 is attached the bottom wall 2 of the collapsible vessel as by means of a bolt 5.

6 is a supporting member preferably trough-shaped for mounting the casing 4 on a heating stove 7. The inverted trough enables the hot air currents ascending the side of the stove to be directed into the casing 4 through openings 7', and circulate around and heat the collapsible and expandable vessel 1, and then pass out of the casing through openings 8.

Attached to the re-entering movable wall 3 of the vessel 1 is a rod 9 passing through the casing 4 and pivoted at its end to a lever 10, which is fulcrumed in a lug 11 attached to the casing 4. Lever 10 is provided at its other end with a guide sleeve 12 loose on a damper rod 13, but held from sliding on this rod by means of adjustable collars 14. Stove 7, which is of the ordinary pattern, is shown as having bottom and top dampers 15 and 16. Damper 15 is provided with a lug 17 cast thereon, having at its outer end a hole receiving a swivel nut 18 loosely mounted therein, held in place by a cotter-pin 20. Independently mounted on one of the bearings for damper 16 is a revolvably supported arm 21 having a shoulder 21' adapted to engage a lug 22 on damper 16. The outer end of arm 21 is also provided with an opening to receive a swivel-nut 23 similar to that of the lower damper. The lower end of rod 13 is screw-threaded and engages swivel-nut 18 while near its upper end is a bushing 28 fast to the rod and engaging nut 23. Rod 13 thus forms an adjustable but rigid connection between dampers 15 and 16. Fast to nut 23 is a heat indicating dial 24 having an index-hand pivoted at 25, provided with an extension 26 for loosely taking around rod 13.

27 is a collar fast to rod 13 which, with bushing 28, prevents the extension 26 from moving lengthwise of rod 13.

29 is a hand-wheel for turning rod 13.

In assembling the heat regulator above described, the re-entering or lower wall of the collapsible vessel should be separated from its opposite wall 2 by a short distance depending on the intended length of traverse of the collapsible vessel, but the distance sepa-

rating these walls should not be so great as to prevent the lower wall reaching the upper one when the vessel is fully collapsed, thereby limiting the extent of contraction of the collapsible wall in an upward direction. A similar limit to the amount of downward extension is also provided by means of the lower wall of casing 4 or by means of an adjustable limiting screw 30. The walls of the vessel are thus prevented from exceeding the elastic limits of its material.

The gaseous body whose expansion and contraction is to be utilized in collapsing and expanding the vessel is introduced into the same in the following manner, the quantity introduced being dependent upon the tension desired within the vessel and the temperature at which the collapsible and expansible vessel is to begin its expansion under the effects of the surrounding heated medium. To charge the vessel to operate for example at a temperature of 170° F. it is filled with carbon dioxid, a portion of which is then pumped out so as to reduce the pressure therein. This causes the pressure of the atmosphere acting on the movable end wall 3 to force it towards wall 2 till it comes in contact therewith. The pressure within the vessel is then further reduced by exhausting a further portion of the gas from the vessel until its tension has been reduced to such an extent that it will have to be raised to a temperature of 170° F. to bring its tension up to atmospheric pressure. The exhaust connection is then hermetically sealed and the regulator coupled to the dampers to be operated in such a manner that when damper 15 is open damper 16 is closed. The extent to which damper 15 is to be opened and the relative positions of the two dampers to each other are adjusted by means of hand-wheel 29, as indicated by the dial 24.

The device having been assembled, as above described, its operation is as follows: Assuming the vessel 1 has been set up to operate in connection with a heating stove, as indicated in Fig. 1, when the stove becomes warm the vessel 1 receives heat both by radiation and convective currents of air directed by and through the support 6 and around vessel 1, when the predetermined temperature is reached the vessel begins to expand downwards, forcing the end 12 of lever 10 up and thereby moving damper 15 towards a closed position. If the air supply is not sufficiently cut off to stop further extension of the vessel 1, it then continues till damper 15 closes, while shoulder 21' engages lug 22 and opens the top draft. This checks the draft at the bottom of the stove and allows cold air to enter at the top, thereby reducing the rate of combustion and preventing the stove from becoming further heated. As the stove cools the vessel 1 cools and the reverse operation

begins. It is preferable to adjust the damper 15 to nearly close the same before shoulder 21' contacts with lug 22. In this way the heat is mainly controlled by damper 15. To adjust the temperature to 70 different degrees the hand-wheel 29 is turned to the right or left as determined by reference to the dial. If the wheel is given a right-hand turn, nuts 18, 23 will be shifted in the direction of the arrow 31, thereby closing damper 15 somewhat and moving part 21' nearer to lug 22. This will cause the regulator to close damper 15 and open damper 16 with less expansion of vessel 1. A reverse turn will have an opposite effect 80 on the length of traverse of the vessel and will hold the stove at a higher temperature.

I have shown the regulator by way of illustration, attached to a stove, but it may be used in connection with an oven, such as a core oven used in foundries, illustrated in Fig. 5. In this case, vessel 1 is supported in the oven without its external casing 4. The vessel properly charged, as above described, with a gaseous body has one rigid end wall 32 fast to a shelf 33 in the oven. The other rigid wall 34 has a stud 35 attached thereto and pivoted to one end of a lever 36, fulcrumed preferably on knife edges 37 in the wall of the oven. The dampers 38, 39 are operated by a chain 40, passing over a pulley 41, fast at 42 to the end of lever 36. The operation of the regulator will be readily understood from what precedes and need not be repeated.

Instead of supporting the regulator as shown in Fig. 1, the bottom of the casing may be open at 43, Fig. 3, to receive the heat from the stove, in which case the bracket 44 may be used to support the 105 device. In this form of regulator a larger part of the heat which reaches the collapsible and expansible vessel is due to radiation. In other respects its operation is like that described in connection with Fig. 1.

In Fig. 4 is shown a further modification in which the supporting arm 45, is made hollow or trough-like to receive a tube 46 connecting the interior of vessel 1 with a gas chamber 47 to be mounted close to or 115' in contact with the side of the stove. This chamber is preferably made broad and shallow, and conforms in a general way to the contour of the stove, thereby giving an extended heat receiving and emitting surface which further increases the efficiency of the regulator. The casing about the collapsible and expansible vessel may be directly attached to the wall of the stove, in which case the stove wall itself may serve as a 120 part of the closure for the vessel.

Although I have described means for limiting the traverse of the collapsible vessel in one and both directions, other means may be suggested such as by tie-rods located inside 130

or outside of the vessel, and secure the advantages of this invention.

It will be noted from the above description that the extent to which the movable end 5 wall is indented governs the volume of gas inside the vessel, and, therefore, any desired degree of expansion with a given change of temperature may be obtained because the amount of increase in the expansion of the 10 gas will depend upon the original volume of gas in the vessel; and that rarefaction of the gas below atmospheric pressure at all temperatures below that at which the regulator or motor is designed to operate renders it insensible 15 to those low temperatures and secures positive action only at the desired temperature.

The device herein described quickly responds to changes in temperature within the 20 predetermined limits, maintains a uniform temperature at any desired temperature, is automatic, and simple in construction.

What is claimed is:—

1. In a thermosensitive damper regulator 25 of the character described, the combination of a hot air detaining casing, a closed collapsible and expansible corrugated metallic vessel, containing a gaseous body under diminished atmospheric pressure, supported with- 30 in said casing and having a stationary rigid end wall and an opposite movable reëntering wall normally in contact with said stationary end wall at temperatures below the predetermined lower temperature limit, stop means 35 for limiting the outward movement of said wall for temperatures above a predetermined upper limit, and a damper operating means connected to the movable end wall.

2. In a thermosensitive damper regulator

of the character described, the combination 40 of a hot air detaining casing, an inverted trough-shaped supporting member for the same and adapted to direct hot air currents to said casing, a closed collapsible and expansible corrugated metallic vessel, containing a 45 gaseous body under diminished atmospheric pressure, supported within said casing and having a stationary rigid end wall and an opposite movable reëntering wall normally in contact with said stationary end wall at temperatures below the predetermined lower temperature limit, stop means for limiting the outward movement of said wall for temperatures above a predetermined upper 50 limit, and a damper operating means connected to the movable end wall.

3. In a thermosensitive damper regulator which remains non-responsive to temperature changes outside predetermined temperature limits and responsive within said 60 limits, the combination of a closed collapsible and expansible metallic vessel containing a gas under diminished atmospheric pressure, said vessel having a stationary rigid end wall and a movable reëntering wall 65 normally in contact with said stationary end wall for temperatures below the lower temperature limit, stop means for limiting the outward movement of said wall, and damper operating means connected to the movable 70 wall.

In testimony whereof, I have signed this specification in the presence of two subscribing witnesses.
